UNITED STATES PATENT OFFICE.

ALFRED CRAIG, OF MITCHAM, ENGLAND, ASSIGNOR TO JAMES PAIN & SONS LIMITED, OF LONDON, ENGLAND, AN ENGLISH LIMITED LIABILITY COMPANY.

TOY BOMB OR PROJECTOR.

Application filed February 16, 1927, Serial No. 168,788, and in Great Britain November 17, 1926.

This invention relates to toy bombs or projectors of the kind in which a quantity of small toys, confetti or other material is arranged in a suitable receptacle so as to be 5 expelled therefrom and showered broadcast by the explosion of a small charge.

According to the present invention, a toy bomb contains paper or other "streamers" e. g. paper strips of substantial length 10 wound up or folded into relatively small compass and adapted to be unrolled by holding one end and throwing the body thereof, such "streamers" being secured by one of their ends to the body or receptacle or other 15 part of the bomb, so that upon explosion of the charge the rolled or folded "streamers" are expelled and thereby caused to unroll.

The body of the bomb may be of a well known form consisting of a cylindrical or 20 other shaped receptacle secured to a suitable base for supporting same for instance upon a table, the charge being contained in the base of the receptacle, and the latter remaining after explosion upon the table or 25 other supporting surface.

One suitable construction in accordance with the invention comprises a cylinder or the like secured to a base as aforesaid with a propelling charge located in the bottom 30 of the cylinder and covered by a loosely fitting disc above which the cylinder is more or less filled with rolled paper "streamers" of various colours or/and shapes. One end of each of these "streamers" is secured, for 35 example by glue, either directly to the mouth of the cylinder or to short lengths of tape or stronger paper or the like which in turn are attached to the mouth of the cylinder. Light toys or other articles if desired may be 40 mixed in with the "streamers", and if the contents are liable to damage or to become ignited by the explosion of the charge when only a single disc is interposed, a wad of felt or the like and a second strawboard disc 45 may be provided. The top of the cylinder may be left open or may be lightly sealed by a paper or other cap. The rolled "streamers" or/and other articles may be wrapped in a paper cover.

50 The usual igniting fuse for the propelling charge instead of projecting laterally through the side of the cylinder or other receptacle may according to a feature of this invention be turned upwards so as to 55 lie close against the exterior of the recep-

tacle where it is retained in any convenient manner as for instance by a binding tape running around the receptacle. In this manner possibility of burning or damaging the surface upon which the bomb is placed is 60 eliminated.

A form of construction in accordance with this invention is illustrated in the accompanying drawing, which shows:

A vertical sectional view of a toy bomb 65 containing rolled "streamers" with their free end secured to the body of the projector.

Referring to this drawing:

Secured to a base A of strawboard, wood or other suitable material is a cylindrical tube B also of strawboard or paper or the like having a reinforcing disc C at the bottom. Glued or otherwise fixed to this disc C is a short length of tube D containing a small explosive charge E, for instance gun-cotton, arranged to be ignited by a fuse F which projects laterally through a hole in the receptacle B and, according to a feature of the invention is turned up to lie close 70 against the side of the receptacle and secured by a band of paper or tape G, instead of projecting from the side of the receptacle as hitherto usual.

Fitted over the tube D is a second short 75 length of tube H carrying a strawboard or other disc J which covers in the propelling charge E. To prevent injury to the contents of the cylinder by explosion of the charge a "wad" K of paper, felt or the like is 80 placed on the disc J and covered by a second 85 disc L of similar material.

Filled in on top of the disc L is a number 90 of rolled "streamers" M of paper or the like which have their free ends M¹ passed over the mouth of the container B and secured 95 thereto for example by glue. If desired these free ends of the "streamers" may be made of textile tape or of stronger paper than the remainder of the "streamers". The mouth of the cylinder B is closed by a disc 100 N which sits upon the edge of the receptacle so as to resist external pressure and is sealed by a paper cap O.

The propelling charge E is shown as concentrated centrally within the receptacle B, but it will be obvious that it may simply be spread over the disc C if desired and covered by the disc J. Furthermore the "wad" K and disc L may be dispensed with although 105 their use obviates the possibility of the 110

"streamers" M being set alight or damaged by the explosion of the charge.

What I claim is:-

1. A toy bomb comprising a receptacle 5 permanently secured to a suitable base, an explosive charge in the bottom of said receptacle, means for igniting said charge and a number of rolled streamers located in said receptacle above said explosive charge and 10 having their free ends secured to the body of the receptacle so that upon explosion of the charge the said streamers are expelled from the mouth of the receptacle and due to their attachment thereto are caused to unroll and spread out in the air.
2. A toy bomb comprising a receptacle 20 permanently secured to a suitable base, an explosive charge in the bottom of said receptacle, a container for said explosive charge of smaller diameter than the receptacle and located substantially centrally in the bottom thereof, means for igniting said charge, and a number of rolled streamers located in said receptacle above said explosive charge and having their free ends secured to the receptacle so that upon explosion of the charge said streamers are expelled from the mouth of the receptacle and are caused to unroll and spread out in the 30 air.
3. A toy bomb comprising a receptacle 35 permanently secured to a suitable base, an explosive charge in the bottom of said receptacle, means for igniting said charge, and a number of rolled streamers located in said receptacle above the said charge and having their free ends secured to textile fabric tapes which are in turn attached to the receptacle so that upon explosion of the 40 charge the streamers are expelled from the mouth of the receptacle and due to their at-

attachment thereto are caused to unroll and spread out in the air.

4. A toy bomb comprising a receptacle 45 permanently secured to a suitable base, an explosive charge in the bottom of said receptacle, a fuse communicating with said charge and extending through the side of the receptacle and bent so as to lie close to the exterior thereof to prevent damage to the surface upon which the bomb is supported, means to secure the external portion of the fuse in the bent position, and a number of rolled streamers located in said receptacle above the explosive charge and 50 having their free ends secured to the receptacle so that upon explosion of the charge said streamers are expelled from the mouth of the receptacle and due to their attachment thereto are caused to unroll and spread 55 out in the air.

5. A toy bomb comprising a receptacle 60 permanently secured to a suitable base, an explosive charge in the bottom of said receptacle, a fuse communicating with said 65 charge and extending through the side of the receptacle and bent so as to lie close to the exterior thereof to prevent damage to the surface upon which the bomb is supported, means to secure the external portion 70 of the fuse in the bent position, and a number of rolled streamers located in said receptacle above the explosive charge and having their free ends secured to textile fabric 75 tapes which are in turn attached to the receptacle so that upon explosion of the charge the streamers are expelled from the mouth of the receptacle and due to their attachment thereto are caused to unroll and spread out in the air.

ALFRED CRAIG.
